UNITED STATES PATENT OFFICE

2,496,108

ELECTRIC CONDUCTOR EXTENSION CORD

Maurice G. Steele, Rome, N. Y.

Application April 9, 1947, Serial No. 740,413

1 Claim. (Cl. 174—117)

1

This invention relates to electrical conductors, and more particularly to an electrical extension cord incorporated into the structure of a "scatter" rug.

One object of the invention is to provide an electrical rug connector of the above nature which may be easily moved whenever desired from one location to another, in order to connect appliances which are remote from an electric outlet.

A further object is to provide a rug connector of the above nature in which the conductor cord will be concealed within the body of the rug without affecting the ornamental appearance of said rug and without noticeable upward projections.

A further object is to provide an electric rug connector of the above nature, in which the intermediate portion of the cord will be secured to or woven into the rug and having a plug and a socket located beyond the ends of said rug.

A further object is to provide an electric rug extension cord of the above nature, in which the conductor wires may either be woven into the rug fabric itself in an invisible manner or may be secured to the undersurface of said rug by a webbing or tape stitched thereto.

A further object is to incorporate conductor wires in the rug in such a manner that the structure of the rug will protect the conductors from damage and from the possibility of short circuits.

A further object is to provide an electric extension rug connector of the above nature, which will be simple in construction, inexpensive to manufacture, easy to install and manipulate, compact, and very efficient and durable in use.

With these and other objects in view, there have been illustrated on the accompanying drawing two forms in which the invention may conveniently be embodied in practice.

In the drawing,

Fig. 1 represents a perspective view of an electrical connector rug embodying the present invention as it appears when attached at one end to a wall outlet socket and at its other end to an extension plug of a toaster located on an adjoining table.

Fig. 2 is a cross sectional view of the same showing how the spaced electric cords are woven into the fabric of the rug.

Fig. 3 is a fragmentary perspective view of the invention illustrating how the spaced conductors are brought together adjacent each other outside the ends of the rug.

Fig. 4 is a fragmentary cross-sectional view, of a modified form of the invention showing how the two spaced conductors may be attached to the un-

2

dersurface of the rug by a strip of webbing secured to said rug by stitching.

The present invention relates generally to electrical wiring extensions, such as are commonly used to connect electrical appliances, such as radios, lamps, toasters, fans, electric irons, percolators, waffle irons, grills, etc. to electric outlets.

The disadvantages of the common form of the electrical extension cord are that it will not lie flat on the floor, and presents a constant hazard to persons moving about the room, who may trip over the cord causing a great deal of inconvenience and embarrassment as well as personal injury or property damage.

15 By means of the present invention, the above and other disadvantages have been avoided by means of a simple, inexpensive, attractive, and safe rug connector.

This is accomplished by combining with a scatter rug, a pair of longitudinal electric insulated conductor wires which are spaced apart in the body of the rug, and are brought close together beyond the ends of the rug, where they are connected to the two-prong plug and the two-aperture socket respectively.

20 This construction permits the electrical appliance to be located at a point remote from the wall outlet, in such a manner that persons may walk over the rug without any danger of entanglement with the connector cord.

25 Referring now to the drawing in which like reference numerals denote corresponding parts throughout the several views, the numeral 10 indicates a large rug on which is located a small scatter rug 11, in the bottom of which are secured a pair of flat stranded conductors 12, 13 arranged in spaced apart relation. The conductors 12, 13 are covered by a pair of tubular insulating coverings 14, 15 and are secured to the rug by weaving into the rows of longitudinal warp threads 16 and transverse woof threads 17, as clearly shown in Fig. 2.

30 Beyond the ends of the rug 11, the flat insulated conductors 12, 13 are brought closely together to form short end cords 18, 19, wherein said insulated conductors are held in abutment as by cement or stitching. The end section 19 terminates in a two-prong plug 20 for detachable insertion in a wall outlet plate 21.

35 It is also within the scope of the present invention to employ an ordinary cylindrical two-wire cord, in which case the outer covering will be stripped from the insulated conductors for that portion of the length of the cord which passes

through the rug, and the abutted insulated wires will be spaced laterally apart at said portion.

It is also within the purview of the invention to provide the scatter rug with a pair of tunnels or channels through which the spaced insulated conductors may be threaded.

The end cord 18 is provided with a two-aperture socket 22, which is adapted to be connected to a two-prong plug 23, on the end of a standard appliance cord 24 leading to a toaster 25 located on a table 26.

In the modified form of the invention shown in Fig. 4, instead of incorporating the spaced flat conductor cords 12, 13 into the rug 11 by weaving, said cords are attached to the undersurface of said rug by means of a strip 27 of webbing into which the conductors have been previously incorporated, as by weaving, which strip is secured to said rug by longitudinal rows of stitching 28.

The conductor wires are preferably covered with durable modern insulating material such as fiber, glass, plastic, etc., which is highly resistant to abrasion and shock, and facilitates concealment in the rug structure and minimizes any tendency toward lumpiness.

One advantage of the present invention is that if desired, the rug connector may be readily attached to an electric outlet in the floor of a room without making a hole in the rug.

While there has been disclosed in this specification two forms in which this invention may be embodied, it is to be understood that these forms are shown for the purpose of illustration only, and that the invention is not to be limited to the specific disclosures, but may be modified and embodied in various other forms with-

out departing from its spirit. In short, the invention includes all the modifications and embodiments coming within the scope of the following claim.

Having thus fully described the invention, what is claimed as new, and for which it is desired to secure Letters Patent, is:

In a floor covering which may serve also as an extension cord for conducting current from an outlet socket to an electrical appliance, a scatter rug, a single pair of spaced-apart insulated flat conductor cords located under said rug and incorporated therewith by means of a longitudinal webbing positioned under said conductors secured to said rug by stitching, said conductor cords being located in substantial abutment with each other at their end sections which extend beyond both ends of said rug, thereby producing a unitary scatter rug and extension cord.
